UNITED STATES PATENT OFFICE

CHARLES W. KING, OF MEMPHIS, TENNESSEE, ASSIGNOR TO J. E. KISSMER AND MARIE PORTER KING

SELF LOCKING ADJUSTABLE BOOT

Application filed April 8, 1929. Serial No. 353,385.

My invention relates to a self locking adjustable tire boot designed to be used for protecting the inner tube in the case of blow-outs and thin places in the tire casing, and 5 which shall not necessitate the boot being vulcanized to the casing.

Heretofore, boots of this character have been usually formed in sizes to fit the different sizes of tires and various means have 10 been employed to secure the sides of the boot to the rim so as to take as much as possible of the strain off of the weak casing.

Difficulties have been encountered with boots of this character due to the fact that 15 the inner diameter of casings is not the same even with tires of the same size and it is extremely difficult to obtain such a fit of the boot around the inner tube as to avoid chafing of the casing where the boot fits around 20 the tube too tightly, or undue strain on the casing where the boot fits around the tube too loosely. Furthermore, where the boot is provided with a self vulcanizing substance to 25 prevent relative movement between the boot and the casing, as soon as a puncture occurs, both the tube and the boot must be discarded and the vulcanizing of the boot to the casing 30 injures the casing.

I have conceived that this end can be most 35 effectively accomplished by providing the boot with means which will act automatically, responsive to the inflation of the inner tube, to permit the inner tube and the boot to expand to a size sufficient to fill the casing and then automatically hold the boot to 40 its fixed size after it has expanded. My improved boot thus overcomes the two major difficulties heretofore common to devices of this character, namely, chafing of the casing or undue strain thereon.

More particularly, my invention contemplates providing a boot which has overlapped portions adapted to permit it to be expanded and contracted within reasonable limits for 45 use with a number of different sized tires and the free edges of the boot are adapted to be secured together in adjusted position by a strap or equivalent means in cooperation with a novel automatic locking means therefor 50 which are engaged between the boot and the

tire or rim so as to be held by pressure from the inner tube.

My invention further contemplates providing the free edges of the boot with securing means which are acted upon by the inflation of the inner tube so as to hold the boot to the proper size for service within the repaired casing without its being dependent upon the strength of the casing to confine and 55 protect the inner tube.

My invention further contemplates employing as a securing means a strap of relatively soft material which is secured to one side of the boot and is adapted to be passed under a guide or tongue which is slotted out of relatively heavy and tough material on the other side of the boot, the pad being so arranged and disposed that the inflation of the tube within the boot acts against the tongue to bind on and lock the strap when the boot 60 has been expanded to fit the cross section of the casing.

My invention further comprises the novel details of construction and arrangements of parts, which, in their preferred embodiment 65 only, are illustrated in the accompanying drawings which form a part of this invention, and in which:—

Fig. 1 is a plan view of my improved boot showing the strap engaged under the clamping guide or tongue, 70

Fig. 2 is a cross-sectional view taken on the line II—II of Fig. 1, showing the boot in operating position in a casing with the clamping tongue engaging the strap, 75

Fig. 3 is a cross-sectional view of the boot removed from the casing, and

Fig. 4 is a longitudinal cross-sectional view enlarged on the line IV—IV of Fig. 1.

Similar reference numerals refer to similar parts throughout the drawings.

I have shown my boot associated with a typical tire casing 5 having within it an inner tube 6, both tube and casing being of standard construction. My improved tire boot 8 is of any standard construction in so far as its body portion that engages the tread portion of the casing is concerned, being made up in any suitable shape and of any suitable material to serve the purposes con- 95

templated. I have found that it may conveniently be made from cord tire scrap and such is my preferred construction.

The boot is preferably made up with overlapping sides 9 and 10 which are designed to provide sufficient overlap to permit the boot to be expanded to fit within a range of tire sizes while maintaining the overlapping condition of the sides. To one side, as 9, of 5 the boot I attach a strap 12 which is made of relatively soft material such as fabric. The strap 12 is attached to the boot by vulcanizing as I have found that rivets extending through the boot are injurious to the inner tube. 10

To the side 10 of the boot I attach an automatic locking means for the strap 12 which locking means is preferably formed of heavy leather or like material in the form of a 20 pad 13 riveted or otherwise secured by fastenings 14 to the boot and provided with a tongue 15 formed by slits 11 in the body of the pad, thereby forming a tongue 15 extending longitudinally of the pad. 25

The slits are long enough to permit the strap 12 to be threaded under the tongue 15 and the boot is adjusted in position for use. It will be understood that before the strap is 30 threaded under the tongue 15, the boot is fitted over the inner tube opposite the blow-out or weakened portion of the casing and when thus applied the strap is threaded under the tongue 15 and drawn tight enough to contract the boot so that it will fit easily 35 into the casing. The pad 13 is preferably arranged opposite the center of the rim 18 and thus lies opposite the space provided between the beads 16 of the casing. The boot is also positioned so that the pad 13 is on 40 the opposite side of the casing from the hole or blowout 17 in the casing which is to be repaired.

As the inner tube is inflated it expands and as it expands the overlapping portions 9 and 45 10 of the boot are caused to gradually slip one on the other, which movement is permitted because the fabric strap 12 is still relatively loosely held under the heavy leather tongue 15, but it will be apparent that as the 50 inflation proceeds and the inner tube and the overlapping portions of the boot are forced down between the beads and into engagement with the tire rim 18, the tongue is forced down into the slots from which it is 55 placed in the pad, and binds with increasing power upon the strap until the strap is gripped and firmly locked when the boot is expanded to the proper size. The strap 12 is preferably of uniform width throughout so 60 as to resist slipping as much as possible. When this occurs, the boot does not expand further but takes on itself the full strain thereafter resulting from the expansion of the inner tube and thus relieves the weakened casing of the strain. Furthermore, as 65

the boot completely fills the casing, there is no possibility of its rubbing and chafing the casing. By this means the boot serves a new and a different purpose from merely interposing a protective body between the inner tube and the blowout or weakened portion of the casing because it actually reinforces the casing while at the same time it serves to protect the inner tube. 70

While I prefer to arrange the pad so as to 75 be pressed against the rim, the same action occurs where the pad is compressed anywhere between the inner tube and the casing so that the device will work regardless of the pad becoming displaced in the casing. It will 80 furthermore be apparent that more than one strap and pad may be employed if desired.

While I have shown my invention in but 85 one form, it will be obvious to those skilled in the art that it is not so limited but is susceptible of various changes and modifications, without departing from the spirit thereof and I desire therefore that only such limitations shall be placed thereupon as are 90 imposed by the prior art or as are specifically set forth in the appended claim.

What I claim is:

In a self locking interchangeable tire boot, the combination with a wheel rim, of overlapping boot side portions, a pad of relatively heavy leather secured to an overlapping edge of the boot and adapted to be engaged by the wheel rim when the boot is in normal position and when the tire is inflated, said pad having slits in the body 95 thereof forming a tongue, and a fabric strap secured to the other side of the boot and threaded under the tongue. 100

In testimony whereof I affix my signature.

CHARLES W. KING.
